UNITED STATES PATENT OFFICE.

BERT C. MAXWELL, OF CANTON, OHIO.

MANIFOLDING BOOK OR PAD.

No. 847,991.

Specification of Letters Patent. Patented March 19, 1907.

Application filed November 23, 1906. Serial No. 344,722.

To all whom it may concern:

Be it known that I, BERT C. MAXWELL, a citizen of the United States, residing at Canton, in the county of Stark and State of Ohio, have invented certain new and useful Improvements in Manifolding Books or Pads, of which the following is a specification, reference being had therein to the accompanying drawing.

10 This invention relates to an improvement in a manifolding pad or book, it pertaining particularly to a pad or book containing slips or sheets arranged for the purpose of making triplicate copies of the subject-matter required, also triplicate copies of some subject-matter desired to be recorded on the slips or leaves of which the book is formed, and duplicate copies of other subject-matter desired to record.

20 Figure 1 is a plan view of a manifolding-book embodying my improvement. Fig. 2 is a plan view of said book with its cover removed and certain of its leaves rolled back to show their formation. Fig. 3 is a section 25 on the line 3 3', Fig. 1. Fig. 4 is an edge view of a sheet of paper folded to form a set of the triplicating-slips used in the book.

In the drawing, A represents as an 30 entirety a blank sheet of paper from which a set of triplicating-slips is formed by folding the sheet twice intermediate of its ends, once along a transverse line B and again along a transverse line C, along which latter line the sheet is preferably perforated or otherwise 35 weakened. The slips 1 and 3 formed at the upper and lower ends, respectively, of each sheet of paper are shown as folded over upon the intervening slip 2 so formed. Slip 1, containing the upper free end of the sheet of 40 paper, is preferably folded down, so as to lie between the slips 2 and 3, slip 3 thus being made the original slip of the set. In order to form a book or pad, a plurality of these sets of triplicating-slips is placed one upon the other in superposed relation, and the sheets 45 of which they are formed are fastened securely together at their upper ends in any suitable manner, preferably as indicated at 4, immediately beneath the transverse line of 50 the fold B, thus binding the slips 1 and 2 into the book or pad. Each of these slips 1 and 2 is weakened or perforated on a transverse line 5 5', respectively, beneath the point at which they are bound together into the pad 55 to facilitate in the detachment or withdrawal

of the sheets of each triplicating set from the book.

Where a set of triplicating-slips is formed from a single sheet of paper, as above described, the under surfaces of slips 1 and 3 60 are preferably coated with carbon or other suitable manifolding material for as much of their length as is essential in order that any impressions made upon the original in the regular course of its use and desired to be 65 transferred will be transferred to both the duplicate and triplicate slips.

Where it is desired to retain either or both the duplicate-slip 1 or triplicate-slip 2 within the pad or book, the perforation or weakening of either or both along the transverse lines 5 5', respectively, may be omitted.

The original slip 3 of each set is free at its upper end, and the book or pad is preferably provided with a cover 6, which folds over 75 upon the sets of triplicate-slips from below. This cover is somewhat shorter than the original slips 3, which extend beyond it, as indicated at 3', and is made of a relatively 80 hard substance which will not readily transfer through it and to the slips beneath it impressions made upon it. The book is intended particularly for use in a one-writing bookkeeping system. In this connection it is desirable to make the slips to be retained 85 by the proprietor for record as small as possible in order to economize filing-space in the fireproof compartment in which the slips should be kept after working hours. Again, for some reason the proprietor may want to 90 keep two copies of certain data to be recorded on the slip handed the customer and only one copy of other data appearing on the customer's slip. For the purpose of illustration I have shown in the drawings a certain book 95 capable of meeting such requirements as last referred to; but the exact relationship of the slips and their respective sizes, together with the form printed on each one of them, may be readily varied to comply with requirements for a system not precisely similar to the one for which this particular book is intended. The uppermost slip 3 of each set in the book is, as shown, intended for a brief record of the business transaction complete. 100 This slip is to be retained and filed by the proprietor. Consequently it should be reasonably small and the form printed upon it free from unnecessary details. It is shorter than the slip 2, and consequently leaves ex- 110

posed above its upper edge a portion 1^a of the slip 1. This slip 1 in the book shown is intended for use in connection with a cash-register. Upon its exposed portion 1^a is printed a form for recording a business transaction in totals. The slip 1 is considerably shorter than the slip 2 and preferably only extends beneath the slip 3 for a distance sufficient to have printed upon it beneath its exposed portion 1^a the part of the form printed upon the upper end of the slip 3.

The form printed upon the slip 2, which goes to the customer, is the same as that printed upon the slip 3, with the addition that above the said printed form may be printed any desired business bill-head, advertising matter, and the like which may be wanted.

Any suitable means for transferring the writing on the original to the duplicate and triplicate slips may be employed. In the drawings, as hereinbefore stated, I have shown portions of the under surfaces of both slips 1 and 3 as coated with a suitable transfer substance. On the slip 3 this coating is discontinued at 3^a, near the upper edge of the slip, to have a clean portion which may be grasped by the fingers without danger of soiling them.

30 The coating on the under surface of the slip 1 extends only to the line 1^b, as the matter recorded above that line is not to be transferred to the customer's slip 3.

With an arrangement and formation of slips such as just described some of the impressions made on the original are duplicated, while others are triplicated, and this is accomplished at one writing and without readjustment of transfer mediums.

40 To operate the book or pad, one grasps the upper end of the uppermost original slip 3, which appears above the upper free edge of the cover 6 and pulls it upwardly and outwardly, and with it the duplicate and triplicate slips 1 and 2, respectively, attached thereto. This triplicate set is then allowed to fall back upon the cover, and the operator records upon it the desired data without transferring impressions to the triplicate sets 45 of slips beneath the cover 6.

50 It will be noted that the slip 1, formed of the upper section of each sheet of paper, is interposed between sheets 2 and 3, formed from the intermediate and lower sections thereof, respectively, and the binding of the slips together is such that slip 1 will always be drawn out and be in its proper place between the upper and lower slips of each set when the uppermost slip 3 of each triplicating set is drawn out over the cover 6.

What I claim is—

1. In a manifolding-pad, the combination of a plurality of superposed sets of triplicating-slips, each set of slips being formed from a single sheet of paper, twice folded trans-

versely intermediate its ends and perforated or weakened along the line of the lower one of said folds, each slip formed from the upper section of one of said sheets of paper being interposed between the slips formed from the intermediate and lower sections thereof, and the slip formed from said lower section being shorter than the one formed from said intermediate section, suitable transfer mediums interposed between the first and the second and the second and the third slips of each set, respectively, and means for binding said sets of slips together, said means engaging at their upper ends both of the slips formed from the upper and intermediate sections of 80 said sheet of paper.

2. In a manifolding-pad, the combination of a plurality of superposed sets of triplicating-slips, each set of slips being formed from a single sheet of paper, twice folded transversely intermediate its ends and perforated or weakened along the line of the lower one of said folds, each slip formed from the upper section of one of said sheets of paper being interposed between the slips formed from the intermediate and lower sections thereof, and the slip formed from said lower section being shorter than the one formed from said intermediate section, and the under surface of the first two slips in each set being coated with a suitable manifolding substance, and means for binding said sets of slips together at their upper ends, at points above the upper ends of the slips formed from the lower section of each sheet of paper forming a set of slips.

3. In a manifolding-pad, the combination of a plurality of superposed sets of triplicating-slips, each set of slips formed from a single sheet of paper, twice folded transversely intermediate its ends and perforated or weakened along the line of the lower one of said folds, and also along transverse lines on both the upper and intermediate sections of each sheet at points adjacent to the transverse line of fold between them, a suitable manifolding substance on the under surface of the first two slips in each set, and means for binding the sets of slips together so as to form stubs arranged between the upper transverse line of fold of each sheet of paper from which a set of slips is formed and the said weakened or perforated lines on the upper and intermediate sections of the said sheet.

4. In a manifolding-pad, the combination of a plurality of superposed sets of triplicating-slips, each set of slips being formed from a single sheet of paper, twice folded transversely intermediate its ends, each slip formed from the uppermost section of one of said sheets of paper, being interposed between the slips formed from the intermediate and lower sections thereof, and means for binding the sets of slips together so as to form a double stub for each set of slips.

5. In a manifolding-pad, the combination 130

of a plurality of superposed sets of triplicating-slips, each set of slips being formed from a single sheet of paper, twice folded transversely intermediate its ends, each slip 5 formed from the uppermost section of one of said sheets of paper, being interposed between the slips formed from the intermediate and lower sections thereof, and the under surface of the first two slips in each set being 10 coated with a suitable manifolding substance, and means for binding the sets of slips together, arranged to form a double stub for each set of slips, one stub for the slip formed from the intermediate section and the other 15 stub for the slip formed from the upper section of the sheet of paper.

6. A manifolding-pad comprising a plurality of superposed sets of combined duplicating and triplicating slips, each set consisting 20 of three slips of differing lengths, the shortest one of which is interposed between the other two, and the uppermost slip of the set lying directly upon both the shortest slip and a portion of the undermost slip of the set, and 25 means for binding the sets of slips together.

7. A manifolding-pad comprising a plurality of superposed sets of combined duplicating and triplicating slips, each set formed from a single piece of paper twice folded 30 transversely intermediate of its ends to form three slips of differing lengths of which the one formed from the intermediate section of the sheet is the longest and the others are folded over upon it, the shortest slip of each 35 set being arranged to lie between the other two, and suitable transfer mediums interposed between the uppermost slip and portions of the second and third slips, and between the second slip and third slip of each 40 set of slips.

8. A manifolding-pad comprising a plurality of superposed sets of combined duplicating and triplicating slips, each set formed from a single piece of paper twice folded 45 transversely intermediate of its ends to form three slips of differing lengths of which the one formed from the intermediate section of the sheet is the longest and the others are folded over upon it, the shortest slip of each 50 set being arranged to lie between the other two, the under surface of the topmost slip of each set of slips being coated with a suitable transfer material which contacts directly with portions of the upper surfaces of both the middle slip and the under slip of the set, and the under surface of the middle slip of 55 the set being coated with a suitable transfer substance.

9. In a manifolding-pad, the combination 60 of a series of superposed sets of combined duplicating and triplicating slips, each set formed from a single piece of paper twice folded transversely intermediate of its ends, and perforated or weakened along the line of 65 the lower one of said folds, and also along

transverse lines on both the upper and intermediate sections of said sheet of paper at points adjacent to the transverse line of fold between them, each slip formed from the upper section of said sheet of paper being 70 shorter than and arranged to lie between the other two slips formed therefrom, and each slip formed from the lower section of said sheet of paper being shorter than the slip formed from the intermediate section of said 75 sheet and arranged to have its under surface contact with portions of the upper surfaces of both of the other slips of the set, and means for binding said sets of slips together.

10. A manifolding-pad comprising a series 80 of superposed sets of combined duplicating and triplicating slips, each set formed from a single sheet of paper twice folded transversely intermediate its ends and perforated or weakened along the line of the lower one of 85 said folds, each slip formed from the lower section of said sheet of paper being shorter in length than the one formed from the intermediate section of said sheet, and each slip formed from the upper section of said sheet 90 of paper being shorter than the other two slips formed therefrom and arranged to lie between them, and suitable transfer material interposed between the uppermost slip and portions of the middle and under slip of 95 each set, and between the middle slip and portions of the under slip of the set.

11. In a manifolding-pad, the combination 100 of a plurality of superposed sets of triplicating-slips, the uppermost and lowermost slips of each set being suitably connected together at their lower ends and the middle and lowermost slip of each set being suitably connected into the pad at their upper ends, and a cover for said pad arranged to fold 105 over onto the sets of slips from the bottom of the pad and to leave exposed above its top edge a portion of the uppermost slip of the set of slips next beneath it.

12. A manifolding-book comprising a plurality of superposed sets of combined duplicating and triplicating slips, each set formed from a single sheet of paper twice folded 110 transversely intermediate of its ends to form three slips all differing in length, of which a 115 slip formed from one end of said sheet is shorter than the other two slips and in use lies adjacent to but a portion of the slip to which it is attached, suitable transfer medium between the adjacent surfaces of the 120 slips of each set which lie, one upon the other, and means at one end of the sets of slips for holding them together in book form.

In testimony whereof I affix my signature in presence of two witnesses.

BERT C. MAXWELL.

DISCLAIMER.

847,991.—*Bert C. Maxwell*, Canton, Ohio. MANIFOLDING BOOK OR PAD. Patent dated March 19, 1907. Disclaimer filed July 30, 1908, by the patentee.

Enters this disclaimer—

“Of claims 1 and 2 of the said patent, which read as follows, to wit:

“1. In a manifolding-pad, the combination of a plurality of superposed sets of triplicating-slips, each set of slips being formed from a single sheet of paper, twice folded transversely intermediate its ends and perforated or weakened along the line of the lower one of said folds, each slip formed from the upper section of one of said sheets of paper being interposed between the slips formed from the intermediate and lower sections thereof, and the slip formed from said lower section being shorter than the one formed from said intermediate section, suitable transfer mediums interposed between the first and the second and the second and the third slips of each set, respectively, and means for binding said sets of slips together, said means engaging at their upper ends both of the slips formed from the upper and intermediate sections of said sheet of paper.

“2. In a manifolding-pad, the combination of a plurality of superposed sets of triplicating-slips, each set of slips being formed from a single sheet of paper, twice folded transversely intermediate its ends and perforated or weakened along the line of the lower one of said folds, each slip formed from the upper section of one of said sheets of paper being interposed between the slips formed from the intermediate and lower sections thereof, and the slip formed from said lower section being shorter than the one formed from said intermediate section, and the under surface of the first two slips in each set being coated with a suitable manifolding substance, and means for binding said sets of slips together at their upper ends, at points above the upper ends of the slips formed from the lower section of each sheet of paper forming a set of slips.”—
